UNITED STATES PATENT OFFICE

VILLEHAD HENRIK FORSSMAN, OF COLOGNE-ON-THE-RHINE, GERMANY

PENCIL

Application filed December 20, 1929, Serial No. 415,549, and in Germany November 19, 1927.

The object of the present invention is to provide lead pencils or the like with strong wood coverings adapted to be satisfactorily sharpened, by employing any desired unseasoned timber and obtaining a very high yield therefrom. It is based upon the discovery that the great stiffness in the longitudinal direction of the lead pencils of selected high grade timber that have hitherto been satisfactory, and also their inclination to favour the cutting in one direction only when being sharpened, are based upon the arrangement of the wood cells in these coverings. Cells of wood are elongated, spindle-shaped hollow beams of great elasticity and strength in relation to their size. In these good pencils they all lie very approximately in the direction of the lead, and therefore have a stiffening effect, and furthermore almost entirely guide the knife, according to their form and arrangement, when cutting in the desired direction.

The invention consists in the manufacture of protective coverings from wood foils with a large number of uncut cells lying in the plane of the foils and of cells lying in other directions mostly cut, these foils being so arranged round the lead, by winding them round it for example, that the direction of the fibres is at least approximately the same as that of the lead.

Such wood foils are delivered, as is known, by a peeling machine for example, with a very large yield, even when preference is given to fresh unseasoned trunks of all kinds of timber. It has been found advantageous to peel roughly, that is to say, to turn the peeling knife to the trunk at quite a large angle to the tangent to the trunk so that it partly cuts and partly shaves. Under these circumstances it pushes the wood fibres still more into the right direction, namely, the direction of the cutting edge. Moreover the foils are then softer and more porous, as a result of which they admit of being coiled better, and subsequently shrink more, that is, form a firmer stick. Timbers or parts thereof which are too hard are thereby equalized.

The invention is illustrated by way of ex-

ample in the accompanying drawings in which

Figure 1 illustrates the peeling operation as applied to a tree trunk,

Figure 2 shows a part of a wood foil peeled off a trunk, and

Figure 3 a pencil lead wound round with such a foil.

Figure 4 is a plan view of the lead pencil, shown in Figure 3.

In Figures 5 and 6 are illustrated devices for shaping and hardening the lead pencil coverings.

The fresh trunk 1 of any desired kind of wood has here to be regarded as being clamped in a peeling machine and a foil 2 as being taken off by a peeling knife 3. The grain therefore runs transversely to the direction of movement of the sheet of wood, and the great majority of the cells, provided the thickness of the foil is adapted to the kind of timber, are not cut through, and lie in the plane of the foil, while cells extending in other directions are cut through. By wrapping the foil 2 round the lead 4 a protective covering 5 is obtained. This protective covering may of course also be produced in other ways with the same result, for instance two or more foils may first be assembled with the grain in the same direction to form a thicker sheet of wood, and thereupon formed into a covering.

In order further to enhance the strength of the covering 5 the latter may be passed through a pressing device, which may for example be constructed in the manner of a nozzle, or consists of a plurality of heated rollers 6 (Figures 5 and 6), the working surfaces of which unite at their positions of contact with the wood covering 5 to form the desired cross-sectional shape. It is also possible to employ a plurality of roller stages in series.

This manufacture of pencil coverings permits of the employment of almost any kind of timber. Hard woods can be made porous by cutting them into foils and soft woods can be hardened by compression. The foils may be worked up into strong coverings with very little binding medium.

What I claim is:—

1. A lead pencil comprising a graphite core and a wrapping of wood foil, the breadth of the wood foil being equal to the length of the pencil.
- 5 2. A lead pencil comprising a graphite core, and a wrapping of wood foil, the breadth of the wood foil being equal to the length of the pencil, the cells of the wood foil that are substantially parallel to the core not being cut through, and the cells that are not substantially parallel to the core being cut through.

10 In testimony whereof I have signed my name to this specification.

15 VILLEHAD HENRIK FORSSMAN.
